US00D582236S

(12) **United States Design Patent**
Chen

(10) **Patent No.:** **US D582,236 S**
(45) **Date of Patent:** **** Dec. 9, 2008**

(54) **PNEUMATIC TOOL**

(75) Inventor: **Lung-Pao Chen**, Hsinchu County (TW)

(73) Assignee: **Sunmatch Industrial Co., Ltd.**,
Hsinchu County (TW)

(**) Term: **14 Years**

(21) Appl. No.: **29/297,261**

(22) Filed: **Nov. 7, 2007**

(51) **LOC (8) Cl.** **08-05**

(52) **U.S. Cl.** **D8/68**

(58) **Field of Classification Search** **D8/14.1,**

(57) **CLAIM**

The ornamental design for a pneumatic tool, as shown and described.

DESCRIPTION

FIG. 1 is a perspective view of a pneumatic tool showing my new design thereof;
FIG. 2 is a right side elevational view thereof;
FIG. 3 is a top plan view thereof;
FIG. 4 is a front side elevational view thereof;
FIG. 5 is a bottom plan view thereof.;
FIG. 6 is a left side elevational view thereof; and,
FIG. 7 is a rear side elevational view thereof.
